UNITED STATES PATENT OFFICE.

WILLIAM F. GRUPE, OF LYNDHURST, NEW JERSEY.

TRANSFER MEDIUM FOR METALLIZING PURPOSES.

Application filed August 20, 1925. Serial No. 51,384.

This invention relates to transfer media for metallizing purposes.

Pursuant to my invention, the usual paper carrier in a sheet or roll form is provided with a layer of metallic particles which is disposed between heat releasable material. In accordance with my invention, upon the passing of the transfer sheet or strip through the tipping or other impression machine, the provision of the heat releasable material on the opposite sides of the metallic particles serves to greatly improve the transfer of the metallic particles from the transfer medium to the article impressed both in "cleanness" of the outline and solidity of the body of the impression.

The heat releasable material serves as a coating on the individual bronze or other metallic particles to prevent tarnishing or other deleterious effect and maintains the brilliancy or tone of the metallic particles.

Further advantages are attained by my invention as will be more clearly understood from the following detail description and the accompanying drawings, in which—

Fig. 1 is a perspective view showing diagrammatically a transfer medium embodying my invention; and

Fig. 2 is a diagrammatic view of another form of my invention.

Referring to Fig. 1 of the drawings, the paper carrier 10 may be of any approved form such as glassine paper, which by its manufacture possesses a highly smooth face. On the face of the paper carrier, pursuant to my invention, a layer of heat releasable material 11 formed of a suitable waxy constituent, preferably with rosin or other resin, is applied. The heat releasable material may be applied to the face of the glassine paper by means of a feeding roll pursuant to the practice as set forth in my previous applications. The bath of the heat releasable material is heated to suitably liquify the material. After the application of the heat releasable material to the paper, the heat releasable material is allowed to become hard upon cooling.

Upon the hardened layer 11 of heat releasable material bronze or other metallic particles 12 are applied in any desirable manner. I prefer to apply the metallic particles by means of a vehicle of a suitable vaporizable medium, whereby the metallic particles are positioned on the heat releasable material as a very thin layer.

I also prefer to combine a "soluble cotton" with the metallic particles, such as acetyl cellulose, nitrocellulose, ammoniated cellulose and the like, or mixtures of the same. In such cases, I employ amyl acetate or the like as the vaporizable vehicle for the metallic particles as well as a solvent for the "soluble cotton."

The deposited coating containing metallic particles is then permitted to dry and harden.

Upon the coating of metallic particles, I apply a layer 13 of heat releasable material such as the heat releasable material 11 deposited directly upon the paper carrier, as aforesaid.

If desired, a sizing 14 of any desired composition or character is applied on the layer of the heat releasable material after it has hardened.

In the use of the metallic medium of the above character, as in the employment of an impression machine for tipping, stamping and like operations, the transfer medium is fed with its paper carrier in contact with the die. The book cover, silk or other article fed by the operator on the platen of the impression machine, is brought into contact with the transfer medium on the paper carrier. The die is heated by an electrical heater or other suitable means to the optimum temperature determined by the constituency of the heat releasable material.

The presence of the heat releasable material on the opposite sides of the metallic particles serves to present the metallic particles instantly for transferring purposes without undue flow of the transfer medium, and a clean and completely filled-out impression is derived. The constituency of the transfer medium also has the advantage of quick cooling and hardening after the transfer operation, which advantage combined with the advantage above named of ready release, enables the speed of the impression machines to be increased under optimum conditions. The layer of heat releasable material which is disposed on the transfer roll strip between the metallic layer and the paper carrier becomes during the heat transfer operation disposed outwardly of the metallic layer and serves as the protective coating for the metallic layer; by reason of its resinous content it shields the metallic layer to a high degree against moisture and other substances encountered in the use

of the article impressed and particularly against perspiration derived from the hands of the operator during the transfer stage.

The presence of the cellulose or "soluble cotton" during the transfer operation effects an enhanced control of the metallic particles during the stage of plasticity of the oppositely disposed layers of the heat releasable material, thus precluding any tendency of undue flowing of the metallic particles. The cellulose or "soluble cotton" ingredient of the layer of metallic particles is also advantageous in effecting the flowing on to a uniform "thickness" of minimum quantity of the metallic particles during the coating stage of the manufacture.

The solution of the "soluble cotton" in its solvent forms a most advantageous vehicle for the metallic particles in the stage of manufacture. The cellulose serves as a medium for conveying and locating the metallic particles and serves also as a protecting coating for the metallic particles.

Another form of my invention comprises the application of the first layer of heat releasable material on the paper carrier and the application of a layer of bronze or other metallic particles on the aforesaid first layer of heat releasable material. Such layer of bronze or other metallic particles is preferably applied by means of a brushing machine, including a brush by which the metallic particles are directly brushed on by the sweeping action of the bristles of the brush. Such procedure results in laying on the bronze or other metallic particles with their flat faces substantially parallel to the face of the heat releasable material. If desired, the brushed on metallic particles may be burnished.

Upon such layer of the metallic particles, I apply bronze or other metallic particles by the procedure set forth hereinabove in respect to my invention illustrated in Fig. 1.

Upon the outer layer of metallic particles, I apply the outer or second layer of heat releasable material, similarly as aforesaid.

The sizing layer, when desired, is applied as the outermost layer.

In Fig. 2, I have illustrated the more specific form of my invention. The paper carrier is indicated at 10, the first heat releasable layer at 11, the brushed-on layer of bronze at 15, the vehicle-applied layer of metallic particles of bronze at 16, the second or outer layer of heat releasable material at 17 and the sizing layer at 18.

My invention is also applicable for the use of the heat transfer medium separate from the paper carrier, which may be manufactured as above set forth and the heat transfer medium separated from the paper by any suitable means mechanically, or by heat, or otherwise, as mechanically by a knife.

The layer of heat releasable material

which on the transfer roll strip is disposed between the metallic layer and the outer sizing layer, during the transfer stage under the condition of the elevated temperature serves as a medium for locating the metallic particles transferred by the impression operation to the article impressed. It is appreciated that such heat releasable layer by reason of its resinous content is less fluid during the stage of heating than the sizing layer, and thereby prevents undue flow of the transferred portion of the transfer medium. Such control of the fluidity of the transferred portion of the transfer material during the transfer stage is also enhanced by the cellulose constituent of the metallic layer, namely by its lesser degree of fluidity at the transfer temperature and its lower co-efficient of heat conduction.

By such transfer operation, such layer of heat releasable material disposed theretofor on the transfer roll strip outwardly of the metallic layer becomes disposed between the metallic layer and the article impressed and thus serves as a protecting layer between the article impressed and the metallic particles, to shield the metallic particles from all chemical action which might otherwise arise due to the chemicals with which the material of the article impressed may have been treated or finished.

The layer of heat releasable material which on the transfer roll strip is disposed between the layer of metallic particles and the paper carrier, by the heat transfer operation becomes disposed outwardly of the metallic particles and serves as a protecting medium in shielding the finished impression from perspiration of the operator encountered in the impression operation and also from moisture and the like incident to the use of the article.

Whereas, I have described my invention by reference to specific forms thereof, it will be understood that many changes and modifications may be made without departing from the spirit of the invention.

I claim:

1. A metallic transfer medium comprising a carrier, a layer of heat releasable material disposed on a face of said carrier, metallic particles disposed on said layer of heat releasable material and a layer of heat releasable material disposed on said metallic particles.

2. A metallic transfer medium comprising a carrier of inert material, a layer of metallic particles and heat releasable material disposed on opposite sides of said layer of metallic particles.

3. A metallic transfer medium comprising a carrier, a layer of heat releasable material disposed on a face of said carrier, metallic particles admixed with cellulose disposed on said layer of heat releasable material and a

layer of heat releasable material and a layer of heat releasable material disposed on said metallic particles.

4. A metallic transfer medium comprising a carrier of inert material, a layer of metallic particles admixed with cellulose disposed thereon and heat releasable material disposed on opposite sides of said layer of metallic particles.

10 5. A metallic transfer medium comprising a layer of heat releasable material, a layer of metallic particles in one face of said layer of heat releasable material and a layer of heat releasable material disposed on said layer of metallic particles.

6. A metallic transfer medium comprising a carrier, a layer of heat releasable material disposed on a face of said carrier, metallic particles disposed on said layer of heat releasable material, a layer of heat releasable material disposed on said metallic particles and a sizing on said second-named layer of heat releasable material.

20 7. A metallic transfer medium comprising a carrier of inert material, a layer of metallic particles, heat releasable material disposed on opposite sides of said layer of metallic particles and a sizing on said second-named layer of heat releasable material.

25 30 8. A metallic transfer medium comprising a carrier, a layer of heat releasable material

disposed on a face of said carrier, metallic particles disposed on said layer of heat releasable material, a layer of metallic particles admixed with cellulose disposed on said 35 first-named layer of metallic particles and a layer of heat releasable material disposed on said metallic particles.

9. A metallic transfer medium comprising a carrier, a layer of heat releasable material 40 disposed on a face of said carrier, metallic particles disposed on said layer of heat releasable material, said layer being applied to locate the metallic particles in substantially parallel relation of the flat faces and 45 a layer of heat releasable material disposed on said metallic particles.

10. A metallic transfer medium comprising a carrier, a layer of heat releasable material disposed on a face of said carrier, 50 metallic particles disposed on said layer of heat releasable material, said layer being applied to locate the metallic particles in substantially parallel relation of the flat faces, a layer of metallic particles admixed 55 with cellulose disposed on said first-named layer of metallic particles and a layer of heat releasable material disposed on said metallic particles.

In testimony whereof I have signed this 60 specification this 18th day of August, 1925.

WILLIAM F. GRUPE.
